gesellschaft, Chemnitz, Germany

Application May 18, 1935, Serial No. 22,253
In Germany July 2, 1934

2 Claims. (Cl. 66—98)

The present invention relates to a selecting device for individually movable presser instruments in straight bar knitting machines.

The problem of bringing individually movable presser instruments commonly or in groups temporarily out of range of the frame needles is solved according to the invention in a simple manner by providing beneath the presser instruments selecting bars and a return bar which act upon projections of the presser instruments.

The device is intended for interrupting the loop formation on the needles provided for knitting the instep portion of a stocking or the like, so that knitting is effected in the heel portions only while the loops of the instep portion are placed in suspense. Furthermore, the device is intended for knitting the beginning row of the sole portions or the like. For this purpose the individually movable presser instruments are brought into different positions of height in the direction of the axis of the frame needles. This is effected by providing the selecting bars with notches, recesses or the like, so that for instance each alternate presser instrument is lifted while the other presser instruments remain in their position of rest.

On account of the different position of height of the presser instruments, one group of the frame needles, i. e. that group of needles lying opposite the lifted presser instruments, is, after sinking, pressed off in a higher position, while the other group, lying opposite the presser instruments which remained in their lower position, is not pressed off at all. By this means the sunk thread loops in the first row, i. e. the beginning row, are shifted over the head of the first, third, fifth, seventh needle and so on but locked in in the head of the second, fourth, sixth, eighth needle and so on, or, vice versa, the sunk thread loops are shifted over the head of the needles of even number, but locked in in the head of the needles of odd number, so that in the second row the formation of new loops may be effected on all the needles in a well known manner.

In the accompanying drawings forming part of the specification two embodiments of the invention are shown by way of example.

Fig. 1 shows in elevation a division with the selecting device for interrupting the loop formation in the instep portion of a stocking or the like.

Fig. 2 is a side elevation of the device shown in Fig. 1.

Fig. 3 is a section on the line 3—3 of Fig. 1.

Fig. 4 shows in elevation a division with the

selecting device for interrupting the loop formation in the instep portion of a stocking or the like and for the formation of a beginning row in the sole portions,

Fig. 5 is a side elevation of the device shown in Fig. 4,

Fig. 6 is a section on the line 6—6 of Fig. 4,

Fig. 7 is a section on the line 7—7 of Fig. 4,

Fig. 8 is a side view showing the selecting device moved into the position ready for operation,

Fig. 9 is a side view similar to that of Fig. 8 showing the selecting device in the elevated position,

Fig. 10 is a front elevation of one of the laterally arranged selecting bars, and

15

Fig. 11 is a detail view of a portion of the device.

Mounted at the jack sinker bearing 1 which, for the sake of clearness, is not shown in Figs. 1 and 4 are, as illustrated in Figs. 2, 3 and 5—9, presser instruments 2 which are held by a bar 3 extending over the whole width of the division. At the lower end of each presser sinker 2 two oppositely directed projections 4 and 5 are provided.

In the frame of the machine, not shown in the drawings, a rock shaft 6 is journaled which extends in the longitudinal direction of the machine in a plane below that of the jack sinker bearing 1. Connected to the rock shaft 6 is a lever 7 carrying at its free end a shiftable roller

30

8 adapted to cooperate with a cam 11 and a circular disc 11' respectively mounted on a cam shaft 10 which also is journaled in the machine frame and extends in the longitudinal direction of the machine in a plane below that of the rock shaft 6. A spring 9, connected with its ends re-

35

spectively to a projection of the lever 7 and to a fixed portion of the machine frame, not shown on the drawings, tends to hold the roller 8 in contact with the cam 11 or with the circular disc 11' de-

40

pending on the position of the roller 8 with respect to the arm 7. Mounted on the rock shaft 6 are arms 12 in which bolts 13 are journaled. Each of the bolts 13 carries a supporting arm 14 at the one end and a supporting arm 15 at the other end. The supporting arms 14 and 15 are

45

drawn against the jack sinker bearing 1 by means of springs 16 connected to said bearing and said arms. The supporting arms 14 carry supporting bars 17, 18. The supporting bar 17 carries a selecting bar 19, while the supporting bar 18, arranged behind the supporting bar 17, carries a selecting bar 20. The selecting bars 19 and 20 are adjustably connected to their supporting bars

50

17 and 18 respectively by means of screws 21 passing through elongated holes 21' in said bars.

55

The number of the presser instruments 2 which may be brought out of the range of the frame needles 30 may be altered by adjusting the selecting bars 19 and 20. The selecting bar 19 extends 5 below projections 4 one of which is provided at the lower end of each of the presser instruments 2 at the front face of same, and the selecting bar 20 extends below projections 5 one of which is provided at the lower end of each of the presser 10 instruments 2 at the rear face of same.

Fixed to the supporting arms 15 is a return bar 22 the upper portion 31 of which is bent. The bent portion 31 of this return bar 22 engages over the rearwardly extending projections 5 of 15 the presser instruments 2.

If the roller 8 on the lever 7 is shifted so as to cooperate with the cam 11 and if then the lever 7 is lifted by means of the cam 11, the arms 12 and thereby the supporting arms 14 and 15 20 are raised. Hereby the presser instruments 2 are raised by means of the selecting bars 19, 20 carried by the supporting bars 17, 18, so that the heads of the presser instruments 2 are brought out of the range of the frame needles 30. The 25 return bar 22 is raised simultaneously and is, on the downward movement of the lever 7, also moved downwardly, carrying with it the presser instruments 2 into their original or exit position.

The selecting bars 19, 20 are provided at that 30 part of the division only at which presser instruments 2 are to be selected. According to the example shown in Figs. 1-3, the selecting bars are intended for interrupting the loop formation on the needles adapted to knit the instep portion 35 of a stocking or the like, so that the heel portions only are knitted, while the loops of the instep portion are placed in suspense.

As the selecting bars 19, 20 are adjustably arranged upon their supporting bars 17 and 18 respectively, the number of the selected presser instruments 2 may exactly be determined by adjusting one or both of the selecting bars.

In the construction shown in Figs. 1-3, it has been supposed, that as a rule presser instruments 2 are selected in the middle portion of the division, where they serve to interrupt the loop formation in the instep portion. The selecting bars may of course also be provided at other portions, for instance at the sides of the division.

50 Instead of adjustably arranging both selecting bars 19, 20, only one of them may be arranged adjustably.

According to the construction shown in Figs. 4-11 additional selecting bars 23 the cross section 55 of which is Z-shaped are also mounted on the supporting bar 17 in each of the divisions. These selecting bars 23 are arranged in the width of the frame needles on which the beginning rows of the sole portions or the like are formed. The 60 selecting bars 23 as a rule occupy an inoperative position and are used in the formation of beginning rows only. The upwardly extending portions 32 of the Z-shaped selecting bars 23 are provided with notches, recesses or the like 24, as 65 clearly shown in Fig. 10. These comb-like selecting bars 23 are provided with elongated holes 33 through which extend screws 33 adapted to adjustably fix them in position.

At each side of each division a plate 25, having 70 an inclined running-on surface 26, is fixed to the jack sinker bearing 1. A rod 27 (Fig. 4) which may be displaced longitudinally is arranged in the supporting arms 14 and guided by means of an additional supporting arm 35 carried by an 75 arm 34 also mounted on the rock shaft 6. Con-

nected to this rod 27 are stops 28 which, as more clearly shown in Fig. 11, are provided with an inclined running-on surface 28', adapted to cooperate with the inclined running-on surface 26 of the corresponding plate 25. As long as the selecting bars 23 are in their inoperative position, the stops 28 are, by means of the springs 16 acting upon the supporting arms 14, drawn against the jack sinker bearing 1, so as to occupy with regard to the plates 25 the position shown in Fig. 11.

If the beginning rows of the sole portions are to be knitted, the rod 27 is moved in any suitable manner in the direction of the arrow X shown in Fig. 4. The inclined surfaces 28' of the stops 28 then run against the inclined surfaces 26 of the plates 25, whereby the supporting arms 14 and the additional supporting arm 35 are oscillated against the action of the springs 16. In this manner the comb-like selecting bars 23 are moved into the range of the rearwardly extending projections 5 of the presser instruments 2 as shown in Fig. 8. If now, in the manner already described, the supporting arms 14 and 15 are raised by means of the cam 11, the presser instruments 2 lying opposite a notch or recess 24 in the upper portion 32 of the comb-like selecting bars 23 remain in their lower position with regard to the jack sinker bearing 1, while the other presser instruments 2 are lifted as shown in Fig. 9. On account of the different positions of height of the presser instruments 2, a beginning row may now be formed by the fact, that by means of the raised presser instruments 2 the heads of the frame needles, affected by them, are pressed off, so that the sunk thread loops are shifted over the head of these needles, while the presser instruments 2 which are not raised do not press off the corresponding frame needles, so that the sunk thread loops are locked in the head of those needles. By adjusting the comb-like selecting bars 23, other groups of presser instruments 2 may be selected. The arrangement may hereby be such that the adjustment may be mechanically effected instead of by loosening the connecting screws 33.

The presser instruments 2 may be directly journaled in the jack sinker bearing 1 or be connected to the latter in a manner to be moved up and down.

What I claim is:

1. In a selecting device for individually movable presser instruments in straight bar knitting machines having a plurality of divisions, a rock shaft extending in front of the divisions of the knitting machine, a spring actuated lever fixed to said rock shaft, a roller adjustably mounted on the free end of said lever, a cam shaft arranged in parallel relation to said rock shaft, a cam and a circular disc fixed to said cam shaft and adapted to cooperate with said roller, an arm mounted on said rock shaft near each end of each division, a bolt journaled in each of said arms, spring actuated supporting arms at both ends of each of said bolts, supporting bars arranged one behind the other and carried by said supporting arms mounted on the end of each of said bolts facing the end of each division, a selecting bar adjustably connected to each of said supporting bars, a return bar carried by said supporting arms fixed to the end of each of said bolts facing the middle of each division, and forwardly and rearwardly directed projections at the lower end of each presser instrument cooperating

with said selecting bars and said return bar respectively.

2. In a selecting device for individually movable presser instruments in straight bar knitting machines having a plurality of divisions, a rock shaft extending in front of the divisions of the knitting machine, a spring actuated lever fixed to said rock shaft, a roller adjustably mounted on the free end of said lever, a cam shaft arranged 10 in parallel relation to said rock shaft, a cam and a circular disc fixed to said cam shaft and adapted to cooperate with said roller, an arm mounted on said rock shaft near each end of each division, a bolt journaled in each of said arms, 15 spring actuated supporting arms at both ends of each of said bolts, supporting bars arranged one behind the other and carried by said supporting arms mounted on the end of each of said bolts facing the end of each division, a selecting bar 20 adjustably connected to each of said supporting bars, a return bar carried by said supporting

arms fixed to the end of each of said bolts facing the middle of each division, forwardly and rearwardly directed projections at the lower end of each presser instrument cooperating with said selecting bars and said return bar respectively, 5 other selecting bars adjustably mounted on the said front supporting bar at the sides of said first mentioned selecting bars, said other selecting bars having a Z-shaped cross section and an upwardly extending portion provided with recesses and lying normally out of the range of 10 said projections of said presser instruments, a rod mounted for longitudinal displacement in said supporting arms carrying said supporting bars, stops fixed to said rod, and plates, having 15 an inclined surface, fixed to said jack sinker bearing, said stops and plates cooperating to bring said other selecting bars provided with recesses 20 into the range of said projections on said presser instruments.

WOLDEMAR HEINITZ.
